DESIGN FOR AN AUTOMOBILE HEADLIGHT LENS

George K. Hundley, Indianapolis, Ind.

Application February 6, 1934, Serial No. 50,637

Term of patent 3½ years

To all whom it may concern:

Be it known that I, GEORGE K. HUNDLEY, a citizen of the United States, and a resident of the city of Indianapolis, county of Marion and State of Indiana, have invented a new, original, and ornamental Design for an Automobile Headlight Lens, of which the following is a specification, reference being had to the accompanying drawing, forming a portion thereof.

In the drawing, Figure 1 is a front elevation of the lens as seen from the rear or inside of the headlamp housing, while Figure 2 is a sectional elevation of the lens taken on the median line of Figure 1.

I claim:

The ornamental design for an automobile headlight lens, substantially as shown.

GEORGE K. HUNDLEY.
